Patented Sept. 7, 1915.

UNITED STATES PATENT OFFICE.

GEORGE A. H. CHURCHILL, OF RUMSON, NEW JERSEY.

BINDING-POST.

1,152,705.

Specification of Letters Patent.

Patented Sept. 7, 1915.

Application filed August 4, 1914. Serial No. 355,047.

To all whom it may concern:

Be it known that I, GEORGE A. H. CHURCHILL, a citizen of the United States, residing at Rumson, in the county of Monmouth and State of New Jersey, have invented a new and useful Binding-Post of which the following is a specification.

This invention relates to a binding post and particularly to certain improvements in devices for securing a wire thereto.

For many purposes it is essential that a binding post shall include means for securing itself to a supporting member in addition to devices for gripping and holding a wire or conductor attached thereto.

It is the principal object of my invention to provide an improved construction of binding post in which these two essential features are embodied in a single element.

In the preferred form of my invention the wire-securing portion is of resilient construction, and the conductor can be attached thereto without the use of tools of any sort.

More specifically the preferred form includes a nut formed of a single piece of wire bent into two concentric spiral coils, one of said coils fitting and engaging the threaded stud and the other coil constituting resilient means for gripping and holding the wire or conductor to be supported.

The device is equally adapted for holding a single wire, or a plurality of wires. In the latter case, any one of the wires may be attached or detached without interfering with the other wires.

My invention further comprises certain devices, arrangements and combinations of parts which will be hereinafter described and more specifically pointed out in the appended claims.

A preferred form of my invention is shown in the drawings, together with certain modifications thereof.

Figure 1 is an elevation of the preferred form of my improved binding post; Fig. 2 is a top plan view of the device shown in Fig. 1; Fig. 3 is a sectional view taken along the line 3—3 in Fig. 1; Fig. 4 is a view similar to Fig. 1 but having the coils of the wire-securing device shown in section; Fig. 5 is a side elevation showing a slightly different form of my invention; and Figs. 6, 7 and 8 are views similar to Fig. 4 but showing other modifications of the invention.

Referring to Figs. 1 to 4, it will be seen that my improved binding post as there shown comprises two elements, a threaded stud A and a wire-securing device or binding nut B mounted thereon. The device B is formed of a single piece of wire and in this form comprises an inner coil C and an outer coil D, these two coils being joined together at their upper ends by the connecting portion E shown in Fig. 2. The inner coil is formed with its diameter and pitch corresponding to the size of the threaded stud A and acts as a screw-threaded nut to secure the device B upon the stud A. The outer coil D is of slightly larger diameter than the coil C and acts to grip and yieldingly hold a conductor W inserted between two or more of its turns. The conductor W may be given one or more turns about the binding post, as shown in Fig. 1, or a straight portion of the wire may be inserted between two of the turns of the coil D, without winding the wire about the binding post. In either case a firm electrical connection is assured. The coils C and D are so spaced from each other, as shown in Fig. 4, that a wire W if forced entirely inside of the coil D, will be held in firm contact between the turns of the coil D and one or more turns of the coil C. The threaded stud A may be mounted upon a supporting member S in any desired manner. In Fig. 1 the stud is shown as being driven or otherwise retained in a hole in the supporting member. In Fig. 5 the threaded stud is shown as constituting part of a headed screw extending through a hole in a projecting lug L which may represent the carbon terminal of a battery. In this figure, the wire-securing device B is firmly screwed on to the stud A and acts to retain the stud within the lug L. At the same time the outer coil D is available for securing the wire or conductor, as in the other figures. The outer turn of the coil D in Fig. 5 is shown as spaced slightly away from the next adjacent turn. This arrangement makes it possible to more easily insert the wire between the turns. After being thus inserted, it can then be moved around the coil until a firm grip is secured and may if desired be thus moved endwise several turns, as indicated by the conductor W in said figure.

In the modified form shown in Fig. 6, the concentric coils C' and D' are shortened and

are arranged longitudinally, the wire or conductor being gripped between the turns of the larger coil, or between the coil and the end portion of the stud A.

5 In Fig. 7 a short intermediate portion of the coil is utilized as the nut, while at both ends the concentric coils are of larger diameter. The lower single coil may be slightly bent to lie in a plane normal to the stud 10 and may be used to secure a conductor W', while one or more additional conductors may at the same time be secured by the turns of the large coil at the upper end of the nut. In this form I have also shown the outer 15 free end of the wire forming the coil as being slightly turned outwardly, similar to Fig. 5, but having the additional advantage that the free end permits a loop of the conductor W' to be slipped over the end and 20 then passed downwardly along the coil.

A still simpler form of the device is shown in Fig. 8 in which the entire coil is of one diameter, the coil extending beyond the stud to afford opportunity for securing the conductor thereto. This is a cheaper form and 25 for small conductors is found quite satisfactory.

The advantages of the binding post herein described will be apparent. No tools are 30 required, either for attaching the device B to the stud A, or for securing the conductor W to the device B. Furthermore, the device occupies no more room than the ordinary screw and check nut most commonly used, 35 and occupies much less room than the usual substitutes for that well known arrangement. The device may also be cheaply manufactured and is equally adaptable for securing a single wire or a plurality of wires 40 to a single binding post.

While the diameter of the several portions of my improved binding post may be varied within rather wide limits, it will be evident that a certain more or less definite relation 45 must exist between the size of the wire, the size of the conductor, and the diameter of the turns of the wire-gripping portion of the device. In particular, this portion must be of such diameter with reference to the 50 size of the conductor that the latter may be readily inserted between adjacent turns of said portion without permanently distorting the same or giving them a permanent set. For commercial reasons the diameter of 55 the stud and the stud-engaging portion of the wire-securing device must be limited in order to reduce the cost of these parts. Accordingly it has been found for most purposes that a device having portions of two 60 different diameters as shown in Figs. 1 to 7 is most satisfactory.

Having thus described certain forms of my invention, it will be evident that other changes and modifications can be made 65 therein by those skilled in the art without

departing from the spirit and scope of my invention as set forth in the claims, and I do not wish to be limited to the details herein disclosed, but

What I claim is:—

1. A binding post comprising a stud, and a conductor securing device, said device comprising a single piece of wire formed in two concentric coiled portions, one of said portions encircling and engaging said stud, and 75 the second portion being supported by the first portion and being of such diameter that it is effective to grip and hold an electrical conductor inserted transversely between adjacent coils thereof.

2. A binding post comprising a threaded stud and a nut, said nut being formed of a single piece of wire and comprising a portion engaging the stud, and a resilient coil integral therewith, said coil being of larger 85 diameter than said portion and being effective to grip and hold an electrical conductor inserted transversely between adjacent turns thereof.

3. A binding post comprising a threaded 90 stud and a nut, said nut being formed of a single piece of wire having one portion bent to form a close spiral coil fitting the thread of said stud, and the remaining portion of said wire comprising a spiral coil of larger 95 diameter and constituting means for securing a conductor in electrical connection with said stud when inserted transversely between adjacent turns thereof.

4. A binding post comprising a threaded 100 stud and a nut, said nut being composed of two concentric spiral coils of wire, the smaller coil fitting the thread of the stud and the larger coil being effective to grip and hold a conductor inserted between the 105 turns thereof.

5. A binding post comprising a threaded stud and a nut, said nut being formed of a single piece of wire bent to form two concentric spiral coils, the smaller coil fitting 110 the thread upon the stud, and the larger coil being effective to grip and hold a conductor inserted between the turns thereof.

6. A binding post comprising a threaded 115 stud and a nut, said nut being formed of a single piece of wire bent to form concentric coils of different sizes, the smaller coil fitting the threaded stud and corresponding in pitch and diameter thereto, and the other coils being effective to hold a conductor inserted between the turns thereof and also to bind a conductor against the surface upon which said stud is supported.

7. A binding post comprising a threaded 125 stud and a nut, said nut being formed of a single piece of wire bent to form two concentric spiral coils, the inner coil fitting the thread upon the stud, and the outer coil 130 enclosing the first named coil and adjacent thereto, said coils being joined at one end

only, and said outer coil being closely wound and effective to grip a conductor inserted between the turns thereof.

8. A binding post comprising a threaded stud and a nut, said nut being formed of a single piece of wire bent to form two concentric spiral coils, the inner coil fitting the thread upon the stud, and the outer coil inclosing the first named coil and adjacent thereto, said outer coil being so spaced from the inner coil that a conductor inserted between the two coils will firmly contact with and be held by, one or more turns of each coil.

15 9. A binding post comprising a threaded stud and a nut, said nut comprising a coiled portion engaging the stud, and a resilient conductor-securing coil integral therewith,

two turns of said coil being slightly separated to permit a conductor to be easily inserted between them.

10. A binding post comprising a stud and a holding device formed of a single piece of wire and having two coils of different diameters, the smaller coil engaging the stud and securing the device thereto, and the larger coil being effective to grip and hold a conductor inserted between the turns thereof.

In testimony whereof I have hereunto set my hand, in the presence of two subscribing witnesses.

GEORGE A. H. CHURCHILL.
